UNITED STATES PATENT OFFICE.

CHARLES HENRY BICALKY, OF ONEIDA, NEW YORK.

PULLEY.

SPECIFICATION forming part of Letters Patent No. 736,926, dated August 25, 1903.

Application filed January 13, 1902. Serial No. 89,525. (No model.)

To all whom it may concern:

Be it known that I, CHARLES HENRY BICALKY, of Oneida, in the county of Madison, in the State of New York, have invented new and useful Improvements in Pulleys, of which the following, taken in connection with the accompanying drawings, is a full, clear, and exact description.

This invention relates to improvements in pulleys, having more particular reference to split sheet-metal pulleys.

The primary object of this invention is to produce a pulley in the most economical and expeditious manner which is adapted for use either as a tight or loose pulley and may be readily secured to or detached from a shaft by any ordinary unskilled mechanic.

A more specific object is to make the pulley as light as possible, this being accomplished by stamping or pressing the hub and spokes from single pieces of sheet metal.

A further object is to stamp or press these sheet-metal sections in such manner as to make them substantially as stiff and durable as they would be if formed from solid castings.

A still further object is to provide a split sleeve within the hub adapted to interlock with said hub and so constructed that when the hub-sections are drawn together the inner faces or edges of the opposite ends of the sleeve are drawn into firm and close gripping engagement with the shaft independently of any set-screws.

To this end the invention consists in the combination, construction, and arrangement of the parts of a sheet-metal pulley, as herein-after described, and pointed out in the claims.

Referring to the drawings, Figure 1 is an end elevation, partly in section, of a pulley embodying the various features of my invention. Fig. 2 is an inner face view of one of the detached halves of the pulley. Fig. 3 is an isometric view of one of the detached sections which forms the hub and spokes.

Similar reference characters indicate corresponding parts in all the views.

In the drawings I have shown a pulley comprising opposite rim-sections 1, opposite hub and spoke sections 2, opposite sleeve-sections 3, rim-clamps 4, and additional clamps 5 for drawing the hub and spoke sections together. The rim-sections 1 may be of any desired form

or size, being here shown as consisting of opposite semicylindrical bands having substantially flat-belt engaging-faces 6 and turned marginal edges 7, these marginal flanges serving to stiffen the rim-sections and form suitable shoulders against which the ends of the clamping-plates of the clamp 4 abut. The meeting ends of the rim-sections are adapted to be drawn firmly into engagement with each other when assembled for forming a substantially unbroken cylindrical belt-surface, being held in this position by the clamps 4, presently described.

The clamps 4 are arranged in sets—one set for each of the meeting ends of the rim-sections. Each of these clamps consists of a series of plates 8, 9, and 10, the plate 8 being secured to the inner face of one of the rim-sections in proximity to its end edge, and substantially parallel therewith and is provided with a tongue 11 and one or more loops 12. This plate 8 preferably extends entirely across the inner face of the rim-section to which it is secured and its opposite ends abut against the inwardly-projecting flanges 7, thereby relieving the strain upon the securing means, such as rivets, which are employed to secure the plate to its rim-section.

The tongue 11 of the plate 8 normally extends beyond the end edge of the rim-section and laps upon the inner face of the adjacent end of the other section for preventing any radial displacement of the meeting ends of the rim-sections and also serving to facilitate the assembling of the pulley upon the shaft in a manner hereinafter described.

The loop or loops 12 of the clamping-head 8 is preferably shorter than its base and is adapted to receive a clamping-bolt or bolts 13, the end of the loop remote from the meeting edges of the rim being cut away for forming a shoulder 14, which serves to receive the head, as 15, of the bolt 13, and prevents its rotation when the nut, as 16, is being placed in position for drawing the rim-sections together.

The plates 9 and 10 are secured to the inner face of the adjacent end of the other rim-section by suitable means, as rivets, the plate 10 being interposed between the plate 9 and the inner face of the rim and being disposed in substantially the same cylindrical plane as the base of the plate 8, and its meeting

edge terminates within the meeting edge of the rim for forming a groove 17 between the plate 9 and inner face of the rim for receiving the tongue 11.

5. The meeting edge of the plate 9 preferably extends beyond the adjacent edge of the tongue 11 and also beyond the meeting edges of the rim-sections for additionally stiffening the meeting edges of the rim from radial displacement, and also for facilitating the assembling of the opposite halves of the pulley upon the shaft. This clamping-plate 9 is also provided with one or more loops 18, which are alined with the loops 12 and receive the 15 bolts 13, the meeting edges of the plates 8 and 9 being normally slightly separated, so that the meeting edges of the rim may be drawn tightly together.

The sections 2 which form the hub and 20 spokes of the pulley are each stamped or pressed from a single piece of sheet metal and are substantially duplicates of each other, being interchangeable, and therefore require no fitting or skill in assembling the parts of the 25 pulley. These sections 2 are stamped or pressed in the desired form, depending somewhat upon the size of the pulley, and in this instance each section comprises a substantially semicylindrical portion 19, forming a 30 half of the hub of the pulley and having oppositely-extending arms 20, forming radial arms or spokes of the pulley, the hub portion having a circumferential rib 19', pressed or stamped outwardly from the body of the material, and the central lengthwise portions of the arms or spokes 20 are also pressed or stamped outwardly, thereby producing a 35 lengthwise rib which serves to materially stiffen the spoke-arms. The outer ends of the 40 spoke-arms 20 of the opposite sections 2 diverge toward the rim at the opposite sides of the meeting edges of the rim-sections and are secured to said rim-sections by securing means, as rivets 20'.

45. As seen in Fig. 3, the raised portions of the arms or spokes 20, adjacent to the body or hub 19, is expanded or widened for forming substantially flat faces 21, which are provided with apertures 22 for receiving the clamping-bolts 5, presently described, it being understood that the apertures 22 of one of the 50 sections are alined with the similar apertures of the other section and that the lengthwise ribs and bosses 21 are stamped in the same operation which forms the semicylindrical body 19. By securing the sections 2 at the ends only and additionally arching the central portions said central portions are free to spring inwardly, the clamps are applied, 55 and the side walls of the arched portions are also free to approach or separate to better grip or release from the bushing or shaft to which the pulley may be secured. The circumferential ribs 19' of one or both of the 60 sections are provided with an aperture 24 for receiving an interlocking-lug provided on the inner sleeve-sections. These inner sleeve-

sections 3 may also be of any desired form or size to conform to the size and shape of the hub, and each is a substantial duplication of 70 the other, being provided with a concave inner face having a substantially central enlargement or semi-annular recess 25 for reducing the thickness of the central portion of the sleeve-section and having opposite 75 semi-annular shaft-engaging faces 26 at the opposite ends of the recess 25. The inner and outer faces of the sleeve-sections are provided with lengthwise grooves or recesses 27 for the purpose of reducing the thickness 80 of the material at a point substantially midway between the meeting edges of the sections 3, and thereby forming each section with opposite yielding jaws adapted to be impinged against the shaft when the central 85 portions of the sections 2 are drawn together by the clamping-bolts 5.

It is obvious from the foregoing description and the accompanying drawings that owing to the fact that the clamping-bolts are arranged at opposite sides of the recesses 25 and 27 and that the thickness of the stock is reduced at the recesses when the hub-sections are drawn together by the clamping-bolts 5 the bearing-faces 26 of the sleeve-sections 95 are forced into engagement with the shaft throughout their entire lengths, and that even though there may be a slight variation in the sizes of the shafts to which the pulley is attached, the lengthwise edges of the bearings 26 are forced firmly into engagement with the shaft throughout their lengths—that is, if the shaft is slightly smaller than the normal bore of the sleeve the inner corners of the meeting edges of the bearings 26 will 105 be forced into engagement with the shaft, and if the shaft happens to be slightly larger than the bore the inner corners of the recesses 27, as well as the corners at the meeting edges of the bearings 26, will be forced into engagement with the shaft throughout their entire 110 lengths. This is a particularly important feature of my invention, and by reducing the thickness of the central portions of the sleeve-sections both transversely and longitudinally 115 it is evident that each section is provided with a series of jaws more or less yielding, but adapted to engage the shaft throughout the length of their bearings at some point in the bearings. As seen in Fig. 1, each of these 120 sleeve-sections is provided with a substantially radial lug 28, which enter the recesses 24 and serve to lock the sleeve and hub sections together.

In the operation of my invention when assembling the pulley the tongue 11 at one side of the pulley is brought into contact with the outer face of the projecting edge of the plate 9, which registers the tongue 11 with the groove 17, whereupon the tongue readily enters the 130 groove 17 and forms a fulcrum or pivot upon which the pulley-sections may be rocked with a certainty that the other tongue and groove will readily interlock with each other, where-

upon the clamping-bolts 13 are inserted in the loops 12 and 18 and the two sections are then clamped together. The pulley may then be used as a loose pulley upon the shaft, or by drawing the hub-sections together by the means 5 the sleeve is thrown into firm engagement with the shaft, thereby locking the pulley to the shaft to be used as a tight pulley.

The operation of my invention will now be readily understood upon reference to the foregoing description and the accompanying drawings, and it will be noted that some change may be made in the detail construction and arrangement of the several sections without departing from the spirit of this invention.

Having thus described my invention, what I claim, and desire to secure by Letters Patent, is—

1. In a pulley, the combination with a split rim, of two sheet-metal sections having their opposite ends secured to the rim and their intermediate portions of greater width than their ends and arched in opposite directions toward the rim, said sections having lengthwise ribs widened at their inner ends for forming flat raised portions adjacent to the arched portions, the raised portions having apertures, and clamping-bolts passed through the apertures.

2. In a pulley, the combination with a split rim, of two sheet-metal sections having their

opposite ends secured to the rim and their intermediate portions of greater width than their ends and arched in opposite directions toward the rim, said sections having lengthwise ribs widened at their inner ends for forming flat raised portions adjacent to the arched portions, the raised portions having apertures, and clamping-bolts passed through the apertures, additional ribs formed circumferentially in the arched portions and provided with apertures, and bushing-sections fitting in the arched portions and having lugs projecting into apertures of the circumferential ribs.

3. In a pulley, a split rim having its sections provided with inturned semi-annular shoulders, clamping devices for drawing the meeting edges of the rim together, said clamping devices abutting against the inturned shoulders of the rim, in combination with opposite sheet-metal sections forming the hub and spokes of the pulley and having their outer ends secured to the inner faces of the rim-sections at opposite sides of the clamping devices.

In witness whereof I have hereunto set my hand this 9th day of January, 1902.

CHARLES HENRY BICALKY.
